(57) **CLAIM**

The ornamental design for packaged transaction cards, as shown and described.

DESCRIPTION

FIG. 1 is a front, top perspective view of packaged transaction cards showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of a packaged transaction cards represents unclaimed subject matter and forms no part of the claimed design. The bolded long dash-short dash lines represent the bounds of the claim and form no part of the claimed design.

1 Claim, 5 Drawing Sheets
